BAG MAKING MACHINE

Adolph Potdevin, Garden City, N. Y., assignor to
 Potdevin Machine Company, Brooklyn, N. Y., a
 corporation of New York

Application February 25, 1938, Serial No. 192,455

15 Claims. (Cl. 93—19)

This invention is directed to bag making machinery in general and more specifically is directed to new and improved apparatus for perforating the bag material preparatory to dividing the material into bag lengths.

My machine is particularly well adapted for the handling of bag making material such as cellulose acetate, cellulose hydrate, glassine, and rubber-like materials such as "Pliofilm", a metallic chloride addition product of rubber. While the machine is adapted for the handling of any of the usual bag materials, it has been designed with the materials specifically mentioned above in mind inasmuch as these materials are difficult to handle in automatic machinery, being very easily torn and having a tendency to cling to and clog the machine.

In general, the present machine provides for continuously advancing the material, forming the same into a tube, perforating the walls of the tubing at bag length intervals and separation or final division of the bag making material into bag lengths along the line of perforations. Final division into bag lengths may be effected in any convenient fashion as, for example, by suddenly imposing an increased longitudinal tension upon the perforated bag tube. The corners of the bag length are preferably trimmed so as to remove the last vestige of any cracks or slightly torn places that may be produced at the bag corners when the tubing is divided into bag lengths.

In the accompanying drawing:

Fig. 1 is a side elevational view in part section of part of a bag making machine embodying my invention;

Fig. 2 is a plan view of the apparatus illustrated in Fig. 1;

Fig. 3 is a section on the line 3—3 of Fig. 2;

Figs. 4 and 5 are cross sectional views of a perforator-plate constituting part of my machine.

Referring to the drawing in detail: 2 designates the bag making material. This material, as above noted, may be cellulose acetate, cellulose hydrate, glassine, "Pliofilm", etc. This material is taken from a supply roll in the usual way and fed into the machine continuously. This equipment is old and has not been illustrated nor will it be described in detail.

50 The material 2 as it passes into the machine is tubed about a former-plate 4, the tubing continuously advancing between a pair of forwarding rollers 6 and from thence to a pair of perforator rollers 8, each of the latter carrying a perforator 10. The functions of the perforators 10 is to per-

forate the tubed material at bag length intervals.

The former-plate 4 is provided with a longitudinally extending groove 12 in its upper face for the reception of a perforator-plate 16. This plate, as is plainly apparent from Fig. 2, extends longitudinally of the machine and its forward end 18 projects beyond the former-plate and is widened to about the width of the former-plate. It will be understood that in its initial forward movement the tubing moves forward relatively to the former-plate and to the perforator-plate.

The forward end of the former-plate 4 is bifurcated and terminates at the rollers 8, as shown at 20, instead of, as in prior practice, terminating at the forwarding rollers 6.

The perforators 10 which, as above mentioned, are carried by the rollers 8, extend, as will be appreciated, transversely of the machine and their shape depends upon the desired shape of the bag ends.

The perforator-plate 16 is a flat metal plate, adapted to be reciprocated intermittently with respect to the former-plate. The rear end of the perforator-plate carries a plate 22 which receives the lower end of a lever 24. This lever is pivoted at 26 and its upper end carries a roller 28 adapted to cooperate with a cam roller 30. The function of the cam roller is to positively retract the perforator-plate as will be brought out herein-
after.

The upper and lower faces of the perforator-plate 16 are provided with grooves 32. The grooves on the upper face of the perforator-plate may be in register with the grooves on the lower face of the plate, as shown in Fig. 4, or in staggered relation thereto, as shown in Fig. 5. The grooves 32 are shown extending longitudinally of the machine but this is merely for purposes of illustration, inasmuch as the direction in which they extend depends upon the shape to be given the end of the bag length. Generally speaking they may be said to extend at right angles to the line of division of the tubing. If the tubing is to be divided straight across then the grooves 32 would extend lengthwise of the machine. On the other hand, if the line of division is diagonal to the tubing then the grooves would extend more or less diagonally of the longitudinal axis of the machine. The spacing of the grooves may vary with different types of material. It will be understood that in operation the tubing is perforated between the grooves, and consequently the spacing of the grooves as well as the width of the grooves must be such that sufficient material is

left unperforated at each operation to enable the tubing after the perforating step to be drawn forward to the next step of the dividing operation.

5 As the tubed material advances about the former 4 and the perforator-plate 16 it enters between the rollers 8, and as the perforators 10 are rotated into engagement with the tubed material above and below the perforator-plate 16 the
10 perforator-plate 16 will be picked up and drawn forward at the same speed as that of the perforators. The perforator-plate prior to this action is stationary. As the tubing and the perforator-plate and the perforators 10 advance, the
15 perforators will perforate the tubed material at the areas between the extending grooves 32, to provide perforations in the tubed material, the line of which will obviously depend upon the shape of the perforators 16.

20 As above pointed out, my improved machine
is particularly well adapted for the handling of
materials which lack great tensile strength and
which are more or less elastic. It is important,
therefore, in perforating the tubing that suffi-
25 cient unperforated material be left to enable
drawing of the tubing through the machine to
continue. It is necessary also that sufficient ma-
terial be left unperforated to avoid opening of
the end of the tubing after perforating, inas-
30 much as the tubing is moving through the ma-
chine at a high rate of speed and if the tubing
should open up after it has been perforated it
will clog the machine.

35 The perforator-plate 16 after the operation of the perforators 10 is retracted by the cam roller 30, but before the perforators pick this plate up again the cam roller 30 rotates out of contact with the lever roller 28, so that when the perforators pick up the plate the plate is free, so far as the cam 30 is concerned, to be moved forward at the speed of the perforators and of the tubing. When the plate reaches the end of its forward stroke the cam 30 has rotated into position fully to retract the perforator-plate, ready for the next 40 cycle of operation.

45 Heretofore it has been the practice to terminate the former-plate 4 at the forwarding rollers 6; as above mentioned, but in the present machine the sides of the forward end of the former-plate have been extended forward past the rollers 50 6 to a point adjacent the rollers 8, as already explained, and as shown at 20. This is of advantage, particularly when handling materials which are somewhat elastic, in that it prevents 55 contraction of the material between the end of the former-plate and the head of the perforator-plate, thereby avoiding plugging of the machine at this point. The practically continuous guide for the tubing provided by extending the former-plate 60 also holds the tubing to a straight path, sidewise displacement being thereby prevented, thereby insuring continuous operation at much higher speeds and with less trouble than heretofore thought possible.

65 During the perforating operation the tubing is engaged by the rollers 34, and hence is under tension, and were the former-plate not extended up to the rollers 8 as above explained the tendency of the tubing to contract laterally between the 70 end of the former-plate and the head of the perforator-plate would be very pronounced.

As the tubing continues its forward motion the perforated area of the tubing passes between the rollers 36 and 38 and the cutters 44 carried by these rollers function to cut through the edges of

the tubed material to provide, at the corners of what is eventually to be the leading end of each bag or the end to be bottomed, a projecting tab 46. The other end of each bag length will at the same time be provided with a cut-out 48 which is complementary to the tabs 46.

The leading end of the tubing by this time has reached the overspeeded rollers 42 and the latter will exert a sudden longitudinal tension on the tubing to complete the dividing of the tubing into bag lengths along the line of the perforations therein, and as the trailing end of each bag length passes the punch 40 the latter will function to trim the cut-outs 48 so that any cracks or splinters at the corners will be eliminated. 10 15

It is to be understood that changes may be made in the details of construction and arrangement of parts herein described within the spirit and scope of my invention.

What I claim is:

1. A machine of the class described comprising in combination a perforator-plate extending lengthwise of the machine and provided on opposite faces with grooves, smooth perforators mounted on opposite sides of said perforator-plate, means for tubing material about the perforator-plate, means for bringing the said perforators and the grooved perforator-plate into operative relation with respect to each other with the smooth perforators extending across said plate intermittently to perforate the tubed material through both walls between the grooves in the perforator-plate and at bag length intervals while leaving intact those portions of the tube overlying said grooves. 25 30 35

2. A machine of the class described comprising in combination a perforator-plate provided on one face with a plurality of grooves disposed side by side, a smooth perforator mounted at the grooved side of the perforator-plate, means for tubing material about the perforator-plate, means for bringing the perforator and perforator-plate into operative relation with respect to each other with the smooth perforator extending across the grooved perforator plate to draw the perforator-plate forward at the speed of the perforator, and to perforate the wall of the tubed material between the grooves in the perforator-plate, while leaving intact the portions of the tubed material overlying said grooves and means thereafter positively to retract the perforator-plate within the tubed material.

3. A machine of the class described comprising in combination a perforator-plate extending lengthwise of the machine and provided on opposite faces with grooves, the grooves on one face registering with the grooves on the opposite face, perforators mounted on opposite sides of said perforator-plate, means for tubing material about the perforator-plate, means for bringing smooth portions of the said perforators and the smooth portions of the perforator-plate intermediate said grooves into operative relation with respect to each other intermittently to perforate the tubed material through both walls between the grooves in the perforator-plate and at bag length intervals while leaving intact those portions of the tubed material overlying the grooves in the perforator plate. 55 60 65

- site sides of said perforator-plate, means for tubing material about the perforator-plate, means for bringing smooth portions of the said perforators and the smooth portions of the perforator-plate intermediate said grooves into operative relation with respect to each other intermittently to perforate the tubed material through both walls intermediate the grooves in the perforator-plate and at bag length intervals while 10 leaving intact those portions of the tubed material overlying the grooves in the perforator plate.
- 5 5. A machine of the class described comprising in combination a former-plate, a perforator-plate slidably mounted in the said former-plate and provided on opposite faces with grooves, smooth perforators mounted on opposite sides of said perforator-plate, means for tubing material about the former-plate and perforator-plate, 15 and means for bringing the said smooth perforators and the perforator-plate into operative relation with respect to each other with the smooth perforators registering with the smooth portions of the perforator plate intermediate the grooves 20 in the plate intermittently to perforate the tubed material through both walls intermediate the said grooves and at bag length intervals while leaving intact those portions of the tubed material overlying said grooves.
- 10 6. A machine of the class described comprising in combination a former-plate, a plate slid- 25 able therein, a pair of rollers immediately adjacent the forward end of the former-plate, and a perforator carried by each of said rollers and cooperating with the faces of said slid- 30 able plate.
- 40 7. A machine of the class described comprising in combination a former-plate, a perforator-plate slidable therein and provided on each face with grooves, a pair of rollers immediately adjacent the forward end of the former-plate, and a perforator carried by each of said rollers extending transversely of the machine and cooperating with said grooves.
- 45 8. A machine of the class described comprising in combination a former-plate, a perforator-plate slidable therein and provided on each face with grooves extending longitudinally of the machine, a pair of rollers immediately adjacent the forward end of the former-plate, a perforator carried by each of said rollers extending trans- 50 versely of the machine and cooperating with said grooves, the sides of the forward end of said former-plate terminating immediately adjacent said rollers.
- 55 9. A machine of the class described comprising in combination a stationary former-plate, a perforator-plate slidable therein, means for continuously advancing tubed material about said plates, a pair of rollers adjacent the forward end 55 of said former-plate, perforators carried thereby and cooperable with the perforator-plate intermittently to draw the same forward at the speed of the advancing tube and simultaneously to perforate the walls of the tube, the former-plate terminating sufficiently far forward to reduce the gap between it and the head of the perforator-plate when the latter is drawn forward to not substantially more than the length of the stroke of the perforator-plate.
- 60 10. A machine of the class described comprising in combination a perforator plate extending lengthwise of the machine and provided on opposite faces with grooves, smooth perforators mounted on opposite sides of said perforator plate, means for tubing material about the perforator plate, means for advancing the 65 tubed material along the plate, means for bringing the perforators into operative relation with respect to the perforator plate intermittently with the smooth perforators extending across the plate, the plate and perforators as well as the 70 tubed material moving at this instant substantially at the same speed and the smooth perforators perforating the tubed material while leaving intact those portions of the material overlying the depressions in the plate, and means 75
- forator plate, means for bringing the said perforators and the grooved perforator plate into operative relation with respect to each other with the smooth perforators extending across said plate, intermittently to effect forward movement of the perforator plate at the same speed as the said perforators and to effect perforation of the tubed material through both walls between the grooves in the perforator plate and at bag length intervals while leaving intact those portions of the tube overlying said grooves.
- 15 11. A machine of the class described comprising in combination a perforator plate having grooves in opposite sides thereof lying side by side, means for advancing, lengthwise of the plate, tubed material disposed about the said perforator plate, smooth perforators mounted on opposite sides of said perforator plate, and means for bringing said perforators intermittently into operative relation with respect to said plate with the smooth perforators extending across the grooved plate to perforate the tubed material at bag length intervals through those portions of the material lying intermediate the grooves of the perforator plate while leaving intact those portions of the material overlying the grooves.
- 20 12. A machine of the class described comprising in combination a perforator plate having grooves in opposite sides thereof lying side by side, means for advancing, lengthwise of said perforator plate, tubed material disposed about the plate, smooth perforators mounted on opposite sides of said perforator plate and extending transversely thereof, and means for intermittently bringing said perforators into operative relation to said plate with the smooth perforators extending across the grooves of the plate momentarily to advance said perforator plate and the tubed material together and simultaneously to 40 perforate both walls of the tubed material between the grooves while leaving intact those portions of the tubed material overlying said grooves.
- 25 13. A machine of the class described comprising in combination a perforator plate having elongated grooves in opposite sides lying side by side, means for advancing tubed material about and lengthwise of said perforator plate, curved smooth edged perforators mounted on opposite sides of said perforator plate, said perforators extending transversely of the perforator plate and across said grooves, and means for rotating said smooth edged perforators to move the perforator plate into operative relation with respect to the perforators and provide a curved row of perforations in the tubed walls while leaving intact those portions of the tube overlying said grooves.
- 30 14. A machine of the class described comprising in combination a perforator plate provided on opposite faces with depressions, smooth perforators mounted on opposite sides of said perforator plate and extending transversely of the machine, means for tubing material about the perforator plate, means for advancing the tubed material along the plate, means for bringing the perforators into operative relation with respect to the perforator plate intermittently with the smooth perforators extending across the plate, the plate and perforators as well as the tubed material moving at this instant substantially at the same speed and the smooth perforators perforating the tubed material while leaving intact those portions of the material overlying the depressions in the plate, and means

thereafter to subject the tubed material to increased tension to divide the material along said perforations.

15. In a machine of the class described, means for advancing a continuous web, means for folding over the edges of the web to form a tube, perforating elements contacting both walls of the tube, one of said elements comprising a plate within said tube, the other element comprising 5 perforators mounted above and below said plate

and tube, one of said elements having grooves in the face thereof at spaced intervals, the smooth portions of said grooved element lying between said grooves registering and cooperating with smooth portions on the other element to 5 perforate both walls of the tube between said grooves while leaving intact those portions of the tube overlying said grooves.

ADOLPH POTDEVIN. 10
